SMOKING PIPE

Romeo J. Bergeron, New York, N. Y.

Application January 3, 1941, Serial No. 372,957

3 Claims. (Cl. 131—202)

This invention relates to a smoking pipe, and more particularly to improvements in the stem of the pipe.

The primary objects of the invention are to provide a pipe having a stem of novel construction that will afford a dry, clean, cool smoke that will not bite the tongue.

A further object is to provide a stem that prevents saliva from the mouthpiece from entering the bowl, thus keeping the bowl dry and free from saliva.

Another object is to provide a stem that prevents the moist products of combustion or condensation from entering the mouth of the smoker.

A still further object is to provide a stem that permits of circulation of smoke in its passage from the bowl to the mouthpiece so as to effect a cooling of the smoke.

Another object is to provide the stem with an absorber, such as a piece of standard pipe-cleaner, that will absorb the moisture or moist products and will keep the stem clean.

A still further object is to provide a stem having a flat bottom surface that serves as a convenient rest for the pipe when not in use.

The stem of the pipe has two longitudinal passages, the upper one of which affords a direct passage between the bowl and the mouthpiece or bit; while the lower one, which is closed except for two spaced apart openings into the upper passage, constitutes a trap for the moist products of combustion or condensation of the tobacco entering from the bowl, and for saliva entering from the bit, said lower passage also permitting of circulation of the smoke whereby the smoke is cooled.

The invention is illustrated in the accompanying drawing, in which—

Figure 1 is a longitudinal section of a pipe embodying the invention;

Fig. 2 is a fragmentary bottom plan view thereof;

Fig. 3 is a vertical section taken on the line 3—3 of Figure 1;

Fig. 4 is a fragmentary longitudinal section of a pipe embodying a modification of the invention;

Fig. 5 is a vertical section on line 5—5 through the stem of the modification shown in Fig. 4; and

Fig. 6 is a fragmentary longitudinal section illustrating a further modification of the invention.

Referring to the drawing, and particularly Figs. 1 to 3, the pipe comprises a bowl 10, a

stem 11, and a bit for mouthpiece 12. These parts may be of any suitable shape or pattern, although I prefer to form the stem with a flat bottom surface 13 to provide a convenient rest for the pipe when not in use. The bowl and stem are preferably made of a single piece of brier-wood but they may be made of other material, and as separate parts suitably secured together.

10 The bit 12 may be made of hard rubber, plastic, or any suitable material, and is formed with a conventional smoke passage 14 and reduced end or coupling sleeve 15.

The present invention relates particularly to 15 improvements in the stem portion 11 which I shall now proceed to describe. The stem has two longitudinally extending passages 16 and 17, separated by a dividing wall or partition 18, and openings 19 and 20 extending through the dividing wall at spaced apart points for the purpose hereinafter described.

The two passages 16 and 17 may be readily 20 formed by drilling the stem. Where the bowl and stem are made of a single piece of wood, 25 the bottom wall may be formed with an opening 21 of a diameter large enough to permit of insertion of a drill at an angle to form the openings 19 and 20 through the interior wall 18. The opening is subsequently closed by a plug 22 which 30 may be fixed or detachable.

The upper passage 16 extends from the end 35 of the stem to a point near the bowl where it is connected with the bowl by a passage 23 of reduced diameter or cross-sectional area. The lower passage 17 is preferably longer than the upper one and may extend substantially the entire length of the stem. The open end of the passage 17 is closed with a detachable screw plug or closure 24 to form a chamber that is closed 40 except for the above mentioned openings 19 and 20. Any suitable absorber, such, for example, as a length of standard pipe-cleaner 25, may be placed in the chamber or passage 17. If desired, the end 26 of the wire core of the pipe-cleaner or absorber 25 may be held detachably by the plug 24 for convenience in withdrawal and replacement.

In the modification of the invention shown 45 in Figs. 4 and 5, the dividing wall 27 is a separate piece of wood or other suitable material secured within the stem 11 by tongue and groove joints 28 or in any other suitable manner.

A further modification is illustrated in Fig. 6 50 wherein the bowl 10 is a separate part having

a screw 29 or the like which is attached to the stem.

In use of the pipe, the smoke is drawn from the bowl through the passage 16 and into the mouth. During its passage the smoke, or part of the smoke, passes into and circulates through the passage 17 and thus affords a cooling action. The moist products of combustion or condensation are trapped through the opening 19 and are caught on the absorber 25 in the chamber 17.

Any saliva entering from the bit is likewise trapped in said chamber and caught on the absorber through the opening 20. To these ends the openings 19 and 20 are preferably disposed as close to the bowl 10 and the bit 12, respectively, as practical.

Various changes and modifications in the construction herein illustrated and described may be made without departing from the scope of the invention as defined in the claims.

What I claim is:

1. In a smoking pipe, a bowl having a stem connected at one end thereto, said stem and bowl having a lower longitudinal passage extending from a point closely adjacent to the front of the bowl and beneath the bottom of the latter and through the opposite end of the stem, and said stem having an upper longitudinal passage communicating at one end with the interior

of the bowl and having its opposite end extending through the opposite end of the stem, a partition extending longitudinally of the stem and separating said passages, a removable absorbent member in the lower passage extending beneath the bowl bottom and terminating adjacent to the said opposite end of the lower passage, a closure for said opposite end of the lower passage, a bit having a part of its inner end disposed over and abutting the closure to conceal the latter and having a second part extending beyond said first named part of the inner end of the bit and into said opposite end of the upper passage, said partition having a pair of spaced openings adjacent the rear of the bowl and the opposite end of the stem respectively to establish communication between the passages.

2. A smoking pipe in accordance with claim 1, wherein the under side of the stem is formed with an opening extending into the lower passage and located between said pair of openings, and wherein there is a closure for said opening in the under side of the stem.

3. A smoking pipe in accordance with claim 1, wherein the closure is threaded into the opposite end of the lower passage and has a substantially flat outer face against which said first named part of the inner end of the bit seats.

ROMEO J. BERGERON.
